UNITED STATES PATENT OFFICE

JOHN J. GILBERT, OF PORT WASHINGTON, NEW YORK, ASSIGNOR TO WESTERN ELECTRIC COMPANY, INCORPORATED, OF NEW YORK, N. Y., A CORPORATION OF NEW YORK

LOADED SIGNALING CONDUCTOR AND METHOD OF SIGNALING

Application filed March 5, 1924. Serial No. 696,981.

This invention relates to inductively loaded signaling conductors, and in particular to long submarine cables.

The main object of the invention is to provide a new improved loaded signaling conductor and a new improved method of signaling over a metallic conductor. In accordance with this object, the invention involves the inductive loading of a signaling conductor differently at different points along its length, and, in general, loading it most heavily in the central portions or portions remote from the terminals and more lightly at or near the terminals. In some cases, the loading is reduced to zero at the terminals; that is, is omitted.

In one aspect of the invention, the grading of the inductive loading is such as to reduce attenuation as much as practicable to produce only small distortion in the received current. In another aspect, the grading is for the purpose of decreasing the sending voltage unbalance or, when such unbalance is not large, to permit the use of balancing networks which are less complicated than those heretofore used. From a different point of view, the invention comprises the grading of the loading of a signaling conductor in such manner as to enable the optimum permeability of the loading material to be maintained throughout the length of the loaded conductor. In still another aspect, the invention pertains to grading the loading of a submarine cable for the purpose of preventing or reducing distortion of the signals due to rapid variations of inductance caused by movement of the cable by ocean waves or currents. A specific object of the invention is the simultaneous accomplishment of two or more of these purposes to a marked degree by loading a signaling conductor differently at different points along its length.

This application is a continuation, in part, of application Serial No. 579,393 filed August 45 3, 1922.

There will first be discussed that aspect of the invention which pertains to reduction of attenuation of the transmitted current and of distortion in the received current. The invention, in all of its aspects, is particularly

applicable to long submarine cables, and the following description is, therefore, confined largely to this type of signaling conductor. However, certain aspects of the invention are applicable also to other signaling conductors.

Fig. 1 of the accompanying drawings is a diagram showing the dependence of resistance and inductance on current magnitude for a certain continuously loaded line; Fig. 2 is a diagram showing the relative intensity of induced voltage for a certain harmonic as a function of magnitude of the fundamental current in a certain continuously loaded line; Fig. 3 is a diagram showing the fundamental current as a function of distance from the sending end in that line; Fig. 4 is a diagram of apparatus suitable for the practice of the invention; Fig. 5 is a detail view illustrating degrees of loading; Fig. 6 and 7 are illustrations of modified forms of loaded cable; Figs. 8 and 9, are vector diagrams that will be referred to in discussing the design of the system; Fig. 10 is a curve showing the increase of unbalance effect with heavier loading and increase of frequency. The specific example here chosen to illustrate the particulars of the present invention, is a modification of that cable and a combination involving the modified cable.

In the specification of Buckley Patent 1,586,874, granted June 1, 1926, it is pointed out that the loading of long ocean telegraph cables has heretofore been found of no practical advantage, but that a very great gain in speed is obtained by loading a 2,000 naut cable with a tape of one of a series of magnetic compositions called "permalloy".

A suitable form of permalloy is obtained by fusing together iron and nickel in the respective proportions of 21½% and 78½% and forming them into a tape of suitable dimensions. This permalloy tape is applied helically to the conductor with the edges abutting. Thereafter the taped conductor is given a heat treatment described in the specification referred to, which leaves the permalloy tape in a condition of very high permeability for low magnetizing forces, many times higher than in the best samples of iron heretofore in use.

The high permeability of the loading material gives the loaded conductor a high inductance, thus diminishing the attenuation, and facilitates the transmission of signals at much higher wave frequencies than has been possible on the unloaded cable conductors heretofore in use.

In the operation of long ocean cables, it has been usual to operate them duplex. For this purpose artificial lines are provided at both ends, each of which simulates the cable to a practicable degree, and the actual cable and the artificial line are connected up as arms of a Wheatstone bridge. In the Buckley patent, previously referred to, the continuously loaded line is disclosed as being operated preferably one way, and in the particular example there considered, the one-way operation was shown to be at about 10 times the speed for the unloaded cable with which comparison was proper. The unloaded cable of the prior art has its message capacity increased somewhat less than 100% by duplex operation, so that the message capacity of the continuously loaded cable operated simplex is more than 5 times the message capacity of the unloaded cable operated duplex.

In theoretical discussions of the transmission characteristics of a loaded submarine telegraph cable, it is generally assumed that the cable parameters

R, the resistance per naut;
L, the inductance per naut,
C, the capacity per naut, and

G, the leakance per naut, are independent of the amplitude of the current in the cable. The attenuation constant per naut for this ideal cable can then be obtained by means of the well-known formula

$$\alpha = R/2\sqrt{C/L} + G/2\sqrt{L/C} \quad (1)$$

However, in the case of certain loaded conductors, and particularly in the case of a long signaling conductor continuously loaded with permalloy, the inductance and effective resistance vary to a considerable extent with variations in the current in the conductor in the range of current amplitudes employed for telegraph signaling. This is due principally to the fact that the permeability of the permalloy is a non-linear function of magnetizing force, and is also due to the rapid increase of hysteresis loss with magnetic flux density. The amount of these variations depends upon the permeability of the loading material and upon the manner in which it is applied to the conductor. For the particular cable of length 2,000 nauts heretofore mentioned, the values of inductance and effective resistance at a given reasonable signaling frequency vary with the current as shown in Fig. 1. As the current increases, both the effective resistance and the inductance increase as shown by the respective curves in Fig. 1. The rate of variation is

much less for small values of current than for large values.

This variation of the cable parameters with varying current involves two effects which will now be noticed. First, the attenuation will be greater than the value computed for the ideal cable from the formula heretofore given for α ; this is on account of the fact that the resistance increases much faster with current amplitude than does the inductance. Second, distortion of the signaling impulse occurs, due to intermodulation between the various frequency components of the transmitted signal, and between the transmitted and the received signaling frequency components where duplex operation is employed.

The magnitude of these phenomena can best be determined by a method of approximation. For purposes of illustration we will consider the case of a short length of loaded conductor for which the inductance and resistance vary with the current in the manner indicated by the formulas,

$$R = R_0 + a_1 I + a_2 I^2, \quad (2)$$

$$L = L_0 + b_1 I + b_2 I^2, \quad (3)$$

where R and L are respectively the values of resistance and inductance of the conductor for a current amplitude I, R_0 and L_0 are the corresponding values for $I=0$ and a_1, a_2, b_1, b_2 are constants. When a current of the form

$$I = I_0 \sin pt \quad (4)$$

flows in the conductor the voltage between the terminals of the conductor will be

$$V = RI + \frac{d}{dt} (LI)$$

or, using Equation 2, 3 and 4,

$$V = R_0 I_0 \sin pt + a_1 I_0^2 (\sin pt)^2 + a_2 I_0^3 (\sin pt)^3 + L_0 I_0 p \cos pt + 2b_1 I_0^2 p \sin pt \cos pt + 3b_2 I_0^3 p (\sin pt)^2 \cos pt = V_0 + V_0' + V_1 + V_2,$$

where

$$V_0 = R_0 I_0 \sin pt + L_0 p I_0 \cos pt,$$

$$V_0' = \frac{3}{4} a_2 I_0^3 \sin pt + \frac{3}{4} b_2 p I_0^3 \cos pt,$$

$$V_1 = b_1 p I_0^2 \sin pt - \frac{1}{2} a_1 I_0^2 \cos 2pt,$$

$$V_2 = -\frac{1}{4} a_2 I_0^3 \sin 3pt - \frac{1}{4} b_2 p I_0^3 \cos 3pt.$$

The resultant voltage can, therefore, be considered as made up of a number of components, which have frequencies equal to, or multiples of, the frequency of the fundamental current, and amplitudes which are functions of the amplitude of the fundamental current. V_0 is the voltage that would exist between the terminals of a conductor having the parameters R_0 and L_0 for all current values when traversed by a current $I = I_0 \sin pt$. V_0', V_1 and V_2 represent the

effect of the variable part of R and L upon V and can be considered as electromotive forces induced in the conductor which give rise to currents of the respective frequencies.

5 The current due to V_0' , being of the fundamental frequency, combines with the current I and tends to decrease the amplitude of the latter. The currents due to V_1 and V_2 are of harmonic frequencies and result in distortion of the current wave from its pure sinusoidal shape. The method just described can be applied to the case of a long submarine cable by dividing the cable into a number of short sections and treating each section as

10 a separate conductor, integrating the separate effects in order to obtain the effect for the entire cable.

The preceding analysis gives merely a first approximation to the actual conditions in the conductor. The next step would be to replace Equation (4) by the new expression for the current and repeat the process of approximation. For the purposes of the present explanation, however, this first approximation is of sufficient accuracy.

It is evident, therefore, that as regards transmission characteristics the loaded submarine cable here in view is equivalent to an ideal cable with R and L at all currents equal to the R and L at small current values, but with voltage of fundamental, harmonic and combination frequencies induced continuously along the cable, the amplitude of the induced voltage at any point being dependent upon the magnitude of the fundamental current at that point. For example, when two sinusoidal currents of respective frequencies f_1 and f_2 are being transmitted over the cable, superposed voltages having the frequencies $f_1, f_2, 2f_1, 2f_2, 3f_1, 3f_2, f_1 + f_2, f_1 - f_2$, etc., will be induced along the cable and the magnitudes of these induced voltages at any point are functions of the amplitudes of the two fundamental currents at that point. The current due to the induced voltage of fundamental frequency is superposed on the current due to the impressed voltage of that frequency and tends to reduce the amplitude of the latter current, thus simulating the effect previously mentioned, that attenuation in the actual loaded cable is greater than in the ideal loaded cable. The voltages of harmonic and combination frequencies represent the distortion of the signal shape due to the modulation previously described. The manner in which the magnitude of one of these induced harmonic voltages for example varies with the fundamental current is shown in Fig. 2. For this purpose the second harmonic (double frequency) is chosen. The amplitude of the second harmonic voltage is at once seen to be large for the higher values of current amplitude but falls off rapidly as the fundamental current is decreased. Thus it will be seen that in a cable practically all the induced

voltage of harmonic frequencies originates in the neighborhood of the sending end because it is there only that the fundamental current has sufficiently great magnitude to produce this effect. This is evident from Fig. 3, which shows the amplitude of the fundamental current at various distances from the sending end, where the fundamental current is sinusoidal and of frequency 60 cycles per second. The fundamental current is reduced in the first few hundred miles of the cable to a value for which, according to Fig. 2, the amplitude of the induced harmonic voltage is very small.

The induced voltages at any point, of which the second harmonic has been considered by way of example, give rise to currents of the same frequency which are transmitted in both directions from the point. The contributions from all points along the cable combine at the terminals to give a resultant current, the magnitude of which can easily be determined by a method which will be indicated presently. These currents may be of sufficient magnitude to cause serious distortion of the signals which are being transmitted over the cable. In the case of operation in one direction at a time, the distortion is much less than in duplex operation, because in the former case the majority of the disturbing voltages, being of high frequency, are considerably attenuated by transmission over nearly the whole cable from the points where they are of considerable magnitude. The effect of the induced voltage of signal frequency, representing the effect of increased attenuation, will be strongly felt, however, the result of it being to decrease the transmission efficiency of the cable. In duplex operation, the induced voltages due to the transmitted signal will interfere seriously with the received signal, since it is practically impossible to simulate in the artificial line, the conditions that exist in the cable. This is especially true because the effect at a cable terminal due to a transmitted signal persists for a longer time than for the ideal cable with constant parameters, and this effect is likely to be of an amplitude comparable with that of the signal from the distant terminal.

Although the foregoing statement has relation primarily to duplex operation, as commonly understood, in which there is actual simultaneous and continuous transmission both ways, it also has application in connection with a somewhat different system of two-way transmission which will now be mentioned. This proposed method of operation involves a few impulses, perhaps only one impulse one way and then alternately receiving a similar group of impulses the other way, and so on. It will be seen at once that the persistence of the effect of sending at one end may amount to a certain degree of interference with the first part of the succeeding received impulses. By the present invention,

these effects near the terminals are minimized and therefore there will be less interference due to persistence of effect from a transmitting interval into the succeeding receiving interval.

The magnitude of the currents at the cable terminal due to the induced voltages is a measure of the departure of the cable from the ideal condition of constant parameters, 10 and in order to secure satisfactory operation of the cable, these disturbances must be kept below a certain limit which depends upon the ability of the receiving apparatus to discriminate between signals and interference.

15 In the present invention this is accomplished by employing for those sections of the cable where disturbances would originate, a type of conductor for which the induced voltages are of smaller amplitude than those 20 encountered in the ordinary type of conductor. In other words, the sections of the cable where the signal current is of large amplitude are constructed in such a manner that the slope of their resistance and inductance characteristics is less for any current amplitude than the slope at the same current amplitude 25 on the curves of Fig. 1. Conductors with such characteristics can be obtained in a number of ways. For example, by decreasing 30 the permeability of the loading material, not only the inductance, but the rate of change of inductance of the conductor is diminished and the variation of the effective resistance is much less than in a conductor 35 of higher inductance, since the flux density, and therefore the hysteresis loss, are smaller. Another way to decrease the slope of the characteristics is to use a smaller thickness of loading material with normal permeability. 40 The resistance due to hysteresis loss is smaller in this case also, since the volume of material is less. Still another way is to use the normal dimensions and permeability of tape, but instead of laying the tape so that the 45 edges of adjacent turns abut, it is laid so that there is an interval between the adjacent turns, as indicated in Fig. 5. This way of decreasing the slope of the characteristics not only reduces the contribution of hysteresis to the effective conductor resistance, but 50 also decreases the variation of inductance by introducing a large air-gap into the magnetic circuit.

A cable section constructed by any of the 55 methods above described will have a smaller efficiency of transmission for that section than a cable in which the normal permalloy loading is employed, since the inductance is diminished along with the slope of the characteristics. It is possible, for instance by the use 60 of a number of parallel layers of loading material, to construct a conductor which has the same transmission efficiency as the normal type of conductor and at the same time possesses characteristics of lesser slope than

the normal type. This is due to the fact that for a given efficiency of transmission a lower value of permeability can be used in multiple layer loading than in single layer loading. This form of graduated loading is shown in 70 Fig. 6. The cost of such a conductor, however, is greater than that of a conductor with only a single layer of loading material. It is obvious that, on the grounds either of cost or transmission efficiency, it is not desirable 75 to construct a cable which employs throughout its length a conductor of any of the special types which have been described.

A somewhat different method of accomplishing the desired result consists in employing conductors of various diameters for the different sections of cable loaded in the same way with material of the same permeability. Since the inductance of the conductor under these conditions is inversely proportional to its diameter, the tapering of inductance may be obtained by varying the conductor diameter, employing a conductor of large diameter near the terminals and conductors of progressively smaller diameters 90 in the middle portion of the cable. This method is also of advantage for the purpose of reducing signal distortion and interference between the received and transmitted signals due to variation of the magnetic characteristics of the loading material, since for a given value of current the value of the magnetic field in the loading material is inversely proportional to the conductor diameter. The loading material is therefore worked at 95 a lower magnetic flux density in the larger conductor and the variations in the resistance and inductance are less, or of course both the diameter of the conductor and the amount of magnetic material per unit length 100 of the cable may be simultaneously varied to produce similar results.

It is proposed, therefore, as an example of the present invention to employ conductors of some such type as here mentioned only in 110 the parts of the cable where the magnitude of the signal current is large; and for the greater part of the cable, where the amplitude of the signal current is such that the magnetic disturbances are negligible, to use 115 a conductor loaded in the usual manner.

As an illustration of a method of design of a cable which is less susceptible to magnetic distortion than the ordinary type of cable, consider a case where signals are to 120 be transmitted from both ends, not necessarily simultaneously and where the decreased slope of resistance and inductance characteristics is obtained by sacrificing permeability. Referring to Fig. 4, the cable 125 is shown at 10 with the conductor 11 (Figs. 5, 6 and 7) surrounded by a helical tape 12 of permalloy. The degree of loading is made least at the ends of the cable 10 and greatest at its middle portion. For conven- 130

ience of manufacture, the cable is made in sections, with uniform loading for each section. The ordinates of the diagram at the upper part of Fig. 4 show the degree of loading at corresponding points along the length of cable which are represented by the abscissæ.

5 A procedure by which the lengths of the conductor sections and the modification of inductance per section may be determined 10 will now be outlined. In other words, this is a procedure for determining a satisfactory shape to give the diagram at the top of Fig. 4.

The cable is divided into sections according to a tentative plan and the values of the 15 fundamental signal currents in each section are determined, and from them, the variations of L and R, and consequently the several induced voltages in the respective sections.

20 It is obvious that the current at a cable terminal, due to the voltages of any combination frequency or harmonic frequency induced in one of the sections of the cable, can be represented vectorially in amplitude and 25 phase. The resultant effect at this frequency, due to the contributions from the entire cable, can then be obtained by combining these vectors by the well known graphical method, which is shown in Fig. 8. For instance, if 30 the cable is terminated in a non-loaded section, only negligible disturbing voltages will be induced in this section and the vector representing the disturbing currents will be zero. 35 The section adjacent to the non-loaded section will contribute an amount represented by the vector "ab" of Fig. 8, the next adjacent section an amount "bc", the next "cd", and so on for all the sections of the cable, and 40 the resultant effect at the terminal, due to all the sections, will be represented by the vector "an", which is obtained by the method known as the polygon of vectors. This process is employed in turn for each of the harmonic 45 and combination frequencies involved in the disturbance.

For each frequency there is an upper limit 50 to the value that the disturbing current can have before it interferes appreciably with the signal. A circle is drawn with the origin of 55 vectors as center and the absolute value of this upper limit as radius, and it is obvious that the condition of non-interference means that the extremity of the vector representing 60 the resultant disturbing current must lie within the circle. If the extremity of the vector falls without the circle, an inspection 65 of the vector diagram will show which of the several components is at fault and how this 70 component can be reduced in order to bring the vector within the prescribed limit. For instance, if the component "ab" in Fig. 8 representing 75 the contribution of the first loaded section of cable, were several times the magnitude shown in the figure, the resultant vec-

tor, "an", would probably fall outside the circle shown by the dotted line and the obvious remedy in this case would be to decrease the amount of loading in this section or to increase the length of the non-loaded section 70 of the cable. On the other hand, the vector diagram may indicate that too great an allowance was made for distortion in the tentative arrangement and that heavier loading can be used in certain sections. The final design of 75 cable is attained when each of the frequencies involved in the distortion satisfies the requirement above described.

The terminal sections of the cable may be constructed of non-loaded conductor so that 80 practically no disturbance will originate in these parts of the cable. The sections may be of such length that the signal current at the end of the non-loaded section is reduced enough so that a section of conductor with 85 a small amount of continuous loading can then be used. This extends out to a point where a higher degree of loading becomes possible, and so on until a point is reached where the most heavily loaded type of cable 90 can be used.

The procedure here stated can be applied for the design of cable for one-way or two-way operation but the final result may be different for the two cases. For a cable to 95 be operated in only one direction at a time the magnitude of the received signal is compared at the receiving terminal with the disturbances due to that signal as sent from the other terminal. Where the cable is to be operated duplex, it is necessary, in addition, to 100 compare with the disturbance due to a signal which has been transmitted from the same receiving terminal.

It may be sufficient to provide non-loaded 105 terminal sections and to load the remaining portion of the cable uniformly. Considerable improvement over uniform loading throughout the cable may thus be effected. The length of the non-loaded terminal sections 110 may be only a few miles, or several hundred miles depending upon local disturbing conditions as well as the current attenuation.

The usual terminal apparatus is indicated 115 diagrammatically in Fig. 4 with the receiver R across the Wheatstone bridge, the equal condensers C in two adjacent arms of the bridge, the transmitter T connected to the apex between the condensers C and the balancing network N_1 – N_4 . This network and 120 the line 10 form two arms of the complete Wheatstone bridge for the corresponding end of the cable. The network is made in sections N_1 , N_2 , etc., corresponding to 125 the sections of the line and of different design accordingly. In a balancing network, far more precision of adjustment is required for the part closest to the bridge, that is, the part N_1 in the figure. It is much easier to 130 construct this part and adjust it precisely

if the corresponding part of the actual line is not loaded, because for the non-loaded line the inductance is very small and the effective resistance is constant, whereas for the loaded line, the inductance is larger and varies with current, and moreover, the effective resistance varies with current. Hence it will be seen that the present modification by which a graduation of loading is employed makes it easier to construct an artificial line to balance the cable than if the cable were loaded to the utmost degree all the way from one end to the other.

In another aspect of the invention, which has been briefly mentioned above, the improvement from graduated loading arises from the fact that an optimum permeability may thus be obtained at all points along the conductor. When large sending currents are used, transmission can be improved by obtaining as nearly as possible the optimum value of loading throughout the length of the cable. The optimum value is that at which the increased gain (as measured for example in miles of standard cable in the well known manner) resulting from a small increase in permeability is just balanced by the resulting increase in eddy currents, hysteresis loss, and dielectric losses. The large currents at the sending end increase the effective permeability above its small-current value, and consequently, if it is desired to have optimum permeability under operating conditions, it will be necessary to employ on the terminal sections of the cable a loading material having a permeability which is less than that used on the remainder of the cable. When, for other reasons herein discussed, it is of advantage to omit the loading from the terminal sections or to make it very light, this added advantage of obtaining or approaching the optimum value of permeability may be simultaneously realized. Thus, in general, the graded or tapered loading has several or all of the advantages herein disclosed, to some degree at least.

An additional advantage of the cable having a tapered loading is that it is easier to balance for duplex operation than a cable that is loaded uniformly for high inductance for all its length. This is due to the fact that the heavier the loading of a cable, the more difficult and expensive is the construction of an artificial line to simulate the cable to within a certain percentage.

The reason why it is easier to construct an artificial line to balance a cable when the loading inductance is small can be seen from the following: Assuming the cable to be uniformly loaded and free from irregularities, the input impedance of the cable in the frequency range where most accurate balance is essential is equal to K , the characteristic impedance of the cable. If the artificial line is constructed of equal sections, each equivalent

to a length s of cable, then the electrical parameters of a section are sR , sL , sG and sC , where R , L , G and C are respectively the resistance, inductance, leakance and capacities of a unit length of cable. The input impedance of the artificial line at the frequency $\frac{p}{2\pi}$ will then be, to a close approximation,

$$Z = K \left[1 + \frac{s^2}{8} (R + jpL)(G + jpC) \right], \quad 75$$

where $j = \sqrt{-1}$ and the "unbalance" due to the lack of equality between the input impedances of the cable and of the artificial line is measured by the expression

$$w = \frac{Z - K}{K} = \frac{s^2}{8} \sqrt{(R^2 + p^2 L^2)(G^2 + p^2 C^2)} = \frac{s^2 P^2}{8} \quad (5)$$

The curves of Fig. 10 give the value of P^2 as a function of frequency for various degrees of loading. The values for the heavily loaded cable are ten to fifteen times those of the non-loaded cable and it is obvious that in order to reduce the unbalance for the loaded cable to the same level as the non-loaded cable unbalance, the sections of the artificial line corresponding to the loaded cable must be about one-quarter the size of the sections in the artificial line corresponding to the non-loaded cable. A given length of loaded cable will, therefore, require four times as many sections of artificial line to balance it as will the same length of non-loaded cable. This involves higher costs and greater complexity of structure of the artificial line.

An additional upper limit on the size of section of the artificial line is set as follows. The process of balancing a cable on which irregularities occur consists in placing on the artificial line irregularities corresponding in magnitude and location to those of the cable. To achieve a given degree of balance at any frequency, it is necessary that corresponding irregularities on the artificial line and on the cable shall differ in location by less than a certain fraction of a wave-length, and the length of section cannot be greater than this amount. In the two cases given above the wave-lengths at a frequency of 60 cycles per second are 100 miles for the loaded cable and 500 miles for the non-loaded cable. Therefore, the upper limit of size of section set by this criterion is again smaller for a loaded than for a non-loaded cable.

Four or five times as many sections will, therefore, be required to balance the cable at a given frequency when it is loaded. This means not only increased expense of construction but greater difficulty of maintaining balance. From practical consideration a limit w_n can be set, corresponding to any degree of loading L_n , which (Equation 5) cannot be decreased for reasons of economy or

80

efficiency. The value of w_n increases as the degree of loading L_n is increased.

It is known that the unbalance, due to a local difference between the impedances of a portion of cable and of the corresponding portion of artificial line is less, the greater the distance of these portions from the terminal. This is due to the fact that on both cable and artificial line the transmitted current is attenuated over the interval between the terminal and the impedance irregularity, and the current reflected from the irregularity is attenuated in a corresponding degree before it can reach the receiving instrument. Therefore, it is evident that the difficulty of constructing and maintaining an artificial line to balance a uniformly loaded cable will be confined largely to a portion of the line within a certain distance from the terminal. The unbalance due to the remainder of the line will be diminished by the attenuation factor so that these sections can be made of larger and more convenient size.

According to one aspect of the present invention it is proposed to simplify the construction of the portion of the artificial line in the neighborhood of the terminal by employing a cable composed of a number of sections of various degrees of loading. It was previously pointed out that corresponding to each degree of loading L_n there is a limit w_n beyond which the unbalance between cable and artificial line cannot be decreased for reasons of economy or efficiency, and that the effect of a given unbalance decreases as it is moved away from the terminal. Starting at the terminal of the cable, as in the methods described above, a section with little or no loading is employed, so that it can be balanced with a comparatively simple type of artificial line. When a point on the cable is reached where it is possible to tolerate greater unbalance in the artificial line, a section of more heavily loaded cable is employed, the loading being such that the unbalance in the corresponding portion of the artificial line is less than the limit for this part of the system. This process is continued until a point is reached where the full degree of loading can be employed without causing severe requirements on the corresponding portion of artificial line.

The method of construction will be understood from Fig. 4. The cable is divided into sections having inductances L_1, L_2 etc., any particular value, L_k being chosen so that the unbalance w_k in the corresponding portion N_k of the artificial line is sufficiently small that the combined effect of these unbalances at the terminals of the receiving apparatus is less than the limit required for duplex operation. At the same time the values w_1 , etc., are large enough so that the corresponding portions of the artificial line are easily constructed and kept in balance.

To illustrate, we will consider the case where the cable contains sections of two degrees of loading, the major portion of the cable being heavily loaded and the terminal sections non-loaded. The characteristic impedances of the two types being Z_2 and Z_1 , respectively, it can be shown that the input impedance Z of the cable is determined to a close approximation by the relation.

$$Z = Z_1 + 2Z_1 \frac{Z_2 - Z_1}{Z_2 + Z_1} e^{-2Px} \quad (6)$$

where P is the propagation constant and x is the length of the non-loaded terminal section. The portions of the artificial line simulating the non-loaded and the loaded sections of cable will have the characteristic impedances

$$\begin{aligned} z_1 &= Z_1(1+w_1) \\ z_2 &= Z_2(1+w_2). \end{aligned}$$

and the input impedance z can be determined from a formula similar to (6). The unbalance current in the receiving apparatus is determined by the quantity

$$\frac{z - Z}{Z} = w_1 + (w_2 - w_1) \frac{4Z_1 Z_2}{(Z_1 + Z_2)^2} e^{-2Px} = v_1 + v_2, \quad (7)$$

where

$$v_1 = w_1$$

and

$$v_2 = (w_2 - w_1) \frac{4Z_1^2 Z_2}{Z(Z_1 + Z_2)^2} e^{-2Px} \quad (8)$$

The quantity v_2 measures the effect in the receiving apparatus of changing, at the point x , from non-loaded to loaded cable. It is evident that w_2 (the unbalance between the loaded cable and the corresponding portion of artificial line) can be much greater than w_1 (the unbalance between the non-loaded cable and its corresponding portion of artificial line) since

$$\frac{4Z_1^2 Z_2}{Z(Z_1 + Z_2)^2}$$

is, from the nature of the quantities concerned, less than or, at most, a little greater than unity, and the exponential is a fraction which decreases rapidly as x is increased. Taking for w_1 and w_2 their limiting values, it is possible to determine a value of x for which

$$\frac{z - Z}{Z} = v_1 + v_2$$

is less than the prescribed value.

The preceding discussion suggests a practical method of design of a cable of the proposed type. A tentative arrangement of sections is selected and the value of $(z - Z)/Z$ is determined as the sum of a number of terms

$$\frac{z - Z}{Z} = v = v_1 = v_2 + v_n,$$

the term v_k being the effect of the unbalance between the k th section of the cable and the corresponding portion of the artificial line.

The various v 's can be represented in amplitude and phase by vectors as shown in Fig. 9. The absolute value of the prescribed limit on unbalance interference is represented by the dotted circuit, and for efficient operation it is necessary that v shall lie within this circle. In case v falls without the circle it is easy to tell which of the components v_1 , etc. is too large, and the design can be changed accordingly.

The method of design that has just been outlined takes no consideration of the effect of distortion and interference due to the loading material, which effect and its remedy were discussed in the first part of this specification. To correct for the effect of distortion and interference, as well as to meet the requirements of a balancing network, the design of the loading must be further modified to meet these additional requirements as outlined above. In certain cases, however, it may be desirable to employ tapered loading for the sole purpose of decreasing sending voltage unbalance or to permit the use of less complicated balancing networks.

When a loaded cable is subjected to the pounding of waves or to the action of ocean currents, the motion of the cable will result in rapid variations of its inductance, which will have a disturbing effect on the signals. For this reason, also, it will be advantageous to reduce the degree of loading in these sections or to remove it entirely.

The preceding considerations apply also to a cable loaded by means of inductance coils. The degree of loading in this case can be regulated by varying either the inductance of the individual coils or the interval of cable between adjacent coils.

What is claimed is:

1. A submarine cable which is inductively loaded for a considerable portion of its length and unloaded in a shallow water portion or portions.
2. A submarine cable continuously heavily loaded with magnetic material for a considerable portion of its length and unloaded in a shallow water portion or portions.
3. A submarine telegraph cable having great attenuation and loaded inductively, said loading being comparatively heavy in a part where the signaling current is relatively small due to its having been attenuated by the cable and comparatively light in a part in which the current is relatively large.
4. A signaling conductor loaded comparatively heavily in a part distant from the sending end and comparatively lightly in a part near the sending end, and in combination therewith a balancing network with parts designed to correspond respectively with the differently loaded parts of the conductor.
5. A signaling conductor, part at least of which is loaded continuously with material the permeability of which is a variable de-

pending on the current in the conductor, the loading being heavy where the signaling current is relatively small due to its having been attenuated by passage through the conductor and comparatively light where the current is relatively large.

6. A signaling conductor, part at least of which has a graduated loading of a material having variable permeability dependent upon the current in the conductor so that the inductance and effective resistance of the conductor vary substantially with the current in the conductor, the degree of loading being greatest where the signaling current is relatively small due to its having been attenuated by passage through the conductor and progressively less in parts where the current is relatively large.

7. A signaling conductor having large attenuation and having non-loaded terminal sections and other sections having progressively heavier loading toward the mid-point of the conductor.

8. A submarine cable having great attenuation comprising a signaling conductor having non-loaded terminal sections at least several miles in length and magnetic material associated with the remaining portion of said conductor to form continuous inductive loading.

9. A submarine cable having great attenuation comprising a signaling conductor, part at least of which has a graduated continuous loading of a nickel-iron alloy having higher permeability than iron at low magnetizing forces, the degree of loading being greatest where the signaling current is relatively small due to its having been attenuated by the cable and progressively less in parts where the current is relatively large.

10. A signaling conductor having great attenuation and having a part, at least, loaded with material whose hysteresis loss is a variable depending upon the current in the conductor, the loading being heavy where the signaling current is small due to its having been attenuated by passage through the conductor and comparatively light where the current is relatively large.

11. An inductively loaded signaling conductor surrounded by solid insulating material, the loading being comparatively heavy in a part in which signal distortion due to variation with current of an electric characteristic of the loaded and insulated conductor is small, and comparatively light in a part in which the signal current is so large that its distortion would be appreciable if heavy loading were applied.

12. The combination with a signaling conductor loaded comparatively lightly in a portion at its sending end and heavily in a portion distant from the sending end, of means for impressing upon said cable at the sending end a signaling voltage of such value that

the resulting current in the lightly loaded section would be unduly distorted by the action of the loading material if heavy loading were there applied, but would be so greatly attenuated before reaching the heavily loaded section that no serious distortion would there occur.

13. A submarine cable heavily loaded throughout a part of its length with a nickel-iron alloy, said alloy having higher permeability than iron at magnetizing forces of a few tenths of a gauss or less and being highly sensitive to mechanical strain, a portion of the cable in shallow water being unloaded.

14. A submarine cable having a non-loaded terminal section and another section which is heavily loaded with magnetic material, and in combination therewith a balancing network with parts designed to correspond, respectively, with the non-loaded and loaded parts of the cable.

15. A submarine cable having large attenuation and having non-loaded terminal sections and other sections having progressively heavier loading toward the mid-point of the cable, and in combination therewith a balancing network with parts designed to correspond, respectively, with the differently loaded parts of the cable.

16. The method of signaling by electric currents over a conductor with high attenuation without serious distortion which consists in subjecting the signaling currents to the reaction of a magnetic flux induced by them in a continuously applied loading material after, and only after, they have become attenuated greatly by passage through an unloaded portion of the conductor.

17. The method of signaling by electric currents over a conductor without serious distortion, which consists in producing a magnetic flux in association with the conductor and making its relative intensity correspond approximately with the reduction of the currents by attenuation.

18. The method of signaling by electric currents over a conductor without serious distortion which consists in subjecting the signaling currents to the reaction of a magnetic flux induced by them, making this reaction relatively great in certain parts of the conductor where the current is relatively small due to its having been attenuated by passage through the conductor and relatively low in certain other parts where the current is larger.

19. The method of signaling by electric currents over a submarine cable conductor without serious distortion which consists in subjecting the signaling currents throughout at least the major portion of the conductor to the reaction of a magnetic flux induced by them, and limiting the flux everywhere so that the hysteresis loss has no appreciable effect.

20. The method of operating a signaling conductor which is inductively loaded comparatively lightly in a portion at its sending end and heavily in a portion distant from the sending end, which comprises employing a signaling current so large that undue distortion would be produced in the lightly loaded portion if it were heavily loaded, but not so large as to cause undue distortion in the heavily loaded portion.

21. The method of balancing the constants of an extended cable, having loaded and non-loaded portions, which comprises separating an artificial line into a plurality of portions and adjusting one of said portions to balance the non-loaded portion of said cable and adjusting another portion of said artificial line for balancing the loaded portion of said cable.

22. The method of balancing the constants of an extended cable, having loaded and non-loaded portions, which comprises separating an artificial line into a plurality of portions, connecting said portions of said artificial line in series whereby one of the portions of said artificial line balances the loaded portion of said cable and another portion of said artificial line balances the non-loaded portion of said cable.

23. A cable system comprising in combination, an extended electric cable having a loaded portion and a non-loaded portion on each end thereof, duplex transmitting and receiving apparatus connected at each end of said cable system and an artificial line connected at each end of said cable system, each of said artificial lines comprising a pair of portions having differing electrical characteristics, one of said portions operating to balance the non-loaded portion of said cable system and the other of said portions operating to balance the loaded portion of said cable system.

24. An electric signaling system comprising in combination, a cable having non-loaded portions at opposite ends thereof and an intermediate loaded portion, transmitting and receiving apparatus for duplex operation connected at opposite ends of said cable and an artificial line connected at each end of said cable, each of said artificial lines including a portion for balancing the non-loaded portion of said cable and a separate portion for balancing the loaded portion of said cable, the portions of said artificial lines being electrically connected in series with said portion of said artificial line for balancing the non-loaded portion of said cable connected adjacent the end of said cable.

25. An electric signaling system, comprising in combination a cable, including a loaded portion and a non-loaded portion at each end thereof, duplex signaling apparatus connected to opposite ends of said cable and an artificial line at opposite ends of said cable,

and connected with said signaling apparatus, said artificial line consisting of a pair of portions, each having electrical characteristics, differing one from the other, the electrical 5 characteristics of one portion of said artificial line simulating the electrical characteristics of the loaded portion of said cable and the other portion of said artificial line having electrical characteristics simulating the electrical characteristics of the non-loaded portion 10 of said cable.

26. An electric signaling system, comprising in combination a cable, said cable having a loaded portion and a non-loaded portion, 15 signaling apparatus connected to each end of said cable and an artificial line connected with each end of said cable, said artificial line having a plurality of portions, one of said portions being arranged to balance the electrical constants of said non-loaded portion 20 of said cable and the other portion of said artificial line being arranged to balance the loaded portion of said cable, said first mentioned portion of said artificial line being connected intermediate the end of said cable 25 and said second mentioned portion of said artificial line.

27. An artificial line, for balancing a cable, having a loaded portion and a non-loaded portion, 30 said artificial line including a pair of separate portions for electrically balancing the loaded portion and the non-loaded portion of said cable, one portion of said artificial line including resistance and capacity, and the other portion of said artificial line 35 including inductance, resistance, and capacity.

28. An artificial line for balancing a cable, having a loaded portion and a non-loaded portion, 40 said artificial line including a pair of separate portions for electrically balancing the loaded portion and the non-loaded portion of said cable, one portion of said artificial line including a resistance and capacity, and the other portion of said artificial line 45 including inductance, resistance and capacity, said last named portion of said artificial line being connected in series with said first mentioned portion of said artificial line with said first mentioned portion of said 50 artificial line interposed between the end of said cable and said second mentioned portion of said artificial line.

29. A submarine cable in which a section 55 near a terminal thereof and a section near the center thereof are loaded with magnetic material, the loading being such that the flux density in the loading material produced by a given small current traversing the first named section is smaller than that produced in the loading material by an equal current traversing the second named section.

30. A loaded submarine cable having the 60 loading material graduated in such a way 65 that a smaller flux density is produced in the

magnetic loading material near a cable end than is produced in the loading material of a section near the center of the cable by the same current density.

31. A loaded submarine cable in which an 70 alternating current of normal signaling frequency transmitted from a terminal induces a smaller ratio of flux density in a terminal section as compared to that induced in a section near the middle than would be the 75 case if the terminal section and the section near the middle were identically loaded.

32. A loaded signaling conductor having 80 sections continuously loaded in which one section is loaded with material of greater permeability than another section.

33. A continuously loaded submarine cable conductor having central portions loaded with material of greater permeability at a given density of signaling current than the 85 permeability of loading of a terminal section at the same density of signaling current.

34. A submarine cable comprising sections of cable the impedances of which vary with 90 variations in current but in different degree 95 for different sections, characterized in this, that the sections undergoing the least variation in impedance over a given range of current intensity are located at points in the cable where the variation in intensity of signaling currents is greatest.

35. A submarine cable in which a section 100 near a terminal thereof and a section near the center thereof are loaded with magnetic material, the loading being such that the variation in the flux density in the loading material produced by a given variation in the current traversing the first section is less than that produced in the loading material by an identical variation in the current 105 traversing the second named section.

36. A submarine cable in which a section 110 near a terminal thereof and a section near the center thereof are loaded with magnetic material, the loading being such that for given variations in current intensity in the two sections the variation in the resistance introduced by the loading material of the first section is less than that of the second section.

37. An electric conductor comprising a plurality of continuously loaded sections, the self-inductance of each section gradually increasing from the ends of the conductor toward one of the sections.

38. An electric conductor comprising a plurality of continuously loaded sections, the self-inductance of each section gradually increasing from one end of the conductor toward the other.

In witness whereof, I hereunto subscribe my name this 28th day of February, A. D. 125 1924.

JOHN J. GILBERT.
